UNITED STATES PATENT OFFICE.

FREDERICK S. BARUS, OF JERSEY CITY, NEW JERSEY.

MACHINE FOR FORMING PAPER TUBES.

SPECIFICATION forming part of Letters Patent No. 606,402, dated June 28, 1898.

Application filed September 13, 1897. Serial No. 651,518. (No model.)

To all whom it may concern:

Be it known that I, FREDERICK S. BARUS, of Jersey City, in the county of Hudson and State of New Jersey, have invented a new and Improved Machine for Forming Paper Tubes, of which the following is a full, clear, and exact description.

The object of the invention is to provide a new and improved machine for forming paper tubes used in the manufacture of fireworks and for other purposes, the machine being very simple and durable in construction and arranged to produce a large number of tubes at each operation.

15 The invention consists principally of a rolling-table, a recessed head on the said table, and a slideable mandrel-frame carrying a revolute mandrel adapted to engage the paper in the said recessed head.

20 The invention also consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement. Fig. 2 is a plan view of the same. Fig. 3 is a transverse section of the same on the line 3 3 of Fig. 2. Fig. 4 is a plan view of the improvement with the parts in a different position. Fig. 5 is a sectional side elevation of the rolling-table, the paper-lifting bar, and the recessed head. Fig. 6 is a similar view with the lifting-bar withdrawn and the paper resting on the head. Fig. 7 is a like view of the same with the mandrel-frame advanced and the mandrel engaging the paper in the recessed head. Fig. 8 is a like view of the rolling-table, the mandrel, and the recessed head in a different position; and Fig. 9 is a sectional side elevation of the rolling-table and the mandrel, showing the winding up of the paper on the mandrel.

The improved machine for forming paper tubes is mounted on a suitably-constructed frame A, supporting at its forward end a slightly-inclined rolling-table B, on which the sheet of paper C is placed, the forward edge of the paper abutting against a gage D, piv-

oted at D' on the sides of the rolling-table B to permit of swinging the said gage out of the way when cutting the paper C into strips by spaced cutting disks or knives E on a shaft 55 journaled in a frame F, provided with a rod F', journaled in the sides of a mandrel-frame G, carrying a mandrel H. The revolute knives E are spaced such a distance apart as to correspond to the length of the tubes to be 60 formed, the cutting edges of the knives being adapted to pass into longitudinally-extending recesses or grooves B', formed on the top of the rolling-table B, as is plainly shown in the drawings.

Now when the paper is placed in position on the rolling-table B and engaged thereon with the gage D then the latter is swung over to the position shown in Fig. 1, and then the frame G is slid forward to cause the knives or 70 disks E to cut the paper C into small strips, each for forming a tube. When this has been done, the frame G is moved back to its former position, so as to leave the single strips of paper free on the rolling-table. The frame F, 75 carrying the knives E, is now swung upward and rearward into the position shown in Figs. 4 and 7 to leave the table free for the rolling of the strips into tubes. A transversely-extending bar I, normally resting in a recess in the 80 rolling-table B, is now pushed upward to lift the forward ends of the strips of paper, as plainly illustrated in Fig. 5, for the insertion of a recessed head J, secured to arms J', attached to a transverse bar J², adapted to rest 85 on blocks K, secured to the top of the rolling-table B, at or near the upper end thereof.

The transverse bar I is secured to the upper ends of arms I', attached to a transversely-extending shaft I², journaled in suitable bearings in the sides of the frame A, and on the said shaft is fastened a lever I³, adapted to be taken hold of by the operator to impart a rocking motion to the shaft I², so as to move the bar I upward to lift the forward ends of 95 the strips of paper, as above mentioned, and shown in Fig. 5. When this takes place, the head J can be readily inserted under the lifted-up ends of the strips of paper, and after this has been done the operator releases the lever 100 I³ to permit the springs I⁴, pressing on the arms I', to return the bar I to its former position, as

shown in Fig. 6, thus leaving the free ends of the strips of paper resting on the head J, as shown in Fig. 6. The operator now slides the frame G again forward, so that the mandrel H passes over the strips of paper and upon the raised end of the strips to press the same into the concave recess of the said head, as plainly indicated in Fig. 7. When this has been done, the operator takes hold of the transverse bar 10 J² to swing the head J over, said head being in engagement with the ends of the strips of paper, so that the head finally assumes the position shown in Fig. 8, thus causing the extreme ends of the paper to be wound around the mandrel to insure a proper rolling up of the strips when turning the mandrel. The mandrel is now turned, and for this purpose is provided at one end with a wheel H', having a handle H², under the control of the operator. 15 As soon as one turn is made the operator can remove the head J from the machine and keep on turning the mandrel to completely wind up the strips of paper on the mandrel. The strips of paper are provided on their top surfaces 20 with a suitable gum or other adhesive substance for properly attaching the several layers to each other. When the strips have been wound upon the mandrel, then the frame G is moved back to its former position, as shown 25 in Fig. 1, and then the operator pulls on the wheel H', so as to withdraw the other end of the mandrel H from its bearing and to cause the several tubes formed on the mandrel to be pushed therefrom to drop down between the 30 sides of the frame A into a suitable receptacle provided for the purpose.

In order to insure a proper withdrawing of the mandrel for removing the tubes, I provide a lateral guideway L for the wheel H', so as 35 to prevent wabbling of the mandrel while pushing the tubes off the same. It is understood that the tube next to the bearing adjacent to the wheel H' abuts against the bearing upon withdrawing the mandrel, so as to cause a pushing off of the rest of the tubes, and when the mandrel is finally withdrawn past the last tube the latter drops down into the receiving-receptacle.

In order to insure a proper cutting of the 40 paper by the knives or cutters E, I provide the frame F with fingers F², extending between the cutters and adapted to pass on top of the paper C when the frame G is first moved upon the rolling-table B, so that the knives 45 cut properly without danger of lifting up the strips of paper when returning the frame to its former position.

It will be seen that by the arrangement described the sheet of paper is first cut into 50 strips, and the strips are then wound up on

the mandrel for forming a large number of tubes at one time.

The machine is very simple and durable in construction and is not liable to get out of order. 65

Having thus fully described my invention, I claim as new and desire to secure by Letters Patent—

1. A machine for forming paper tubes, comprising a rolling-table, a recessed head on the 70 said table, and a slideable mandrel-frame carrying a revoluble mandrel adapted to engage the paper on the said recessed head, substantially as shown and described.

2. A machine for forming paper tubes, provided with a rolling and cutting table, a slideable mandrel-frame, a knife-frame pivoted in the said mandrel-frame and carrying knives for cutting a sheet of paper into strips, and a revoluble mandrel in the said frame, for 80 winding the strips into tubes, substantially as shown and described. 75

3. A machine for forming paper tubes, provided with a rolling-table adapted to support strips of paper, a bar for raising the forward 85 ends of the said strips of paper, and a head having a recess, and removably held on the said table, the said head passing under the raised ends of the said strips of paper, substantially as shown and described. 90

4. A machine for forming paper tubes, provided with a slideable frame carrying a revoluble mandrel, a knife-frame pivoted in the said slideable frame and spaced cutting disks or knives carried by the said knife-frame, for 95 cutting the sheet of paper into strips, the mandrel serving for rolling the strips into tubes, substantially as shown and described.

5. A machine for forming paper tubes, provided with a rolling-table, a gage adapted to 100 be swung upon the said table for placing the sheet of paper in proper position on the table, a recessed head removably held on the said table, and adapted to engage the strips of paper to be rolled into tubes, and a slideable mandrel-frame carrying a revoluble mandrel, for engaging the paper in the said recessed head and for winding the paper into tubes, substantially as shown and described. 105

6. A machine for forming paper tubes provided with a device for lifting one end of the paper, a recessed head adapted to pass under the uplifted end of the paper, and a mandrel for engaging the uplifted end of the paper to press it into the recessed head, substantially 110 as shown and described. 115
